UNITED STATES PATENT OFFICE.

JOHN HARBOLSHEIMER, OF PHILADELPHIA, PENNSYLVANIA.

DISCHARGE-CHUTE FOR WAGONS.

No. 874,334.

Specification of Letters Patent.

Patented Dec. 17, 1907.

Application filed July 22, 1907. Serial No. 384,847.

To all whom it may concern:

Be it known that I, JOHN HARBOLSHEIMER, a citizen of the United States, residing in the city and county of Philadelphia, State 5 of Pennsylvania, have invented a new and useful Discharge - Chute for Wagons and other Vehicles, of which the following is a specification.

My invention relates to an attachment to 10 a coal, grain or other wagon, cart or vehicle, whereby the contents of the vehicle may be chuted laterally therefrom, and consists in providing such attachment with novel means for connecting it with the discharge chute of 15 the vehicle, and with novel means for assisting the material entering the attachment in its outward passage, whereby clogging is prevented, or may be relieved.

Figure 1 represents a perspective view of a 20 chute embodying my invention. Fig. 2 represents a transverse section on line $x-x$, Fig. 1. Fig. 3 represents a section of a portion on line $y-y$, Fig. 1.

Similar letters of reference indicate 25 corresponding parts in the figures.

Referring to the drawings:—A designates the discharge chute of a wagon, the same being of ordinary construction.

B designates a spout, which is adapted to 30 be connected with said chute and direct the material discharged from the wagon in lateral direction, whereby the wagon may remain parallel with the side-walk, and obstructing the street is avoided, this feature 35 *per se* being well known.

The spout B consists of a curved body C and the neck or collar D, said body being 40 removably mounted on said neck, the latter having a forward extension E, which is open at top, and provided on its sides with the downturned lips F, which are adapted to be fitted on the sides of the chute A, thus removably connecting the spout with the same, while the spout is in communication with 45 the chute, and form continuities of each other.

In the upper side or wall of the body C is 50 an opening G, which is occupied by the blade or vane H, which may enter said body and is connected with the crank shaft J, whose bearings are on said body, and which is provided with a handle K, for operating purposes.

It will be seen that the ends of the body 55 C are matched, so that either end of the same may be fitted on the neck D the body

being reversed for that purpose, whereby the contents of the wagon may be discharged towards the sidewalk or elsewhere to the right or left of the wagon, as required, while 60 the wagon remains parallel with the sidewalk, avoiding the turning of the wagon, which otherwise obstructs the street, said contents discharging from the wagon as usual on the chute A and then entering the 65 spout B through which they flow to the desired place.

Should the material clog or congest in the 70 spout or the flow of the same is slow, the vane H is vibrated, so that as it enters the spout it works against said material and agitates the same and pushes it forward, thus 75 relieving the clogging or congestion and causing an efficient discharge of the material.

When the vane is in normal condition, it 80 practically closes the opening G and prevents the escape of the material therethrough.

Chains are provided for sustaining the 85 body and neck in operative position, to which, however, I do not limit myself.

While I have specified certain means for carrying out my improvements, I do not 90 wish to be limited exactly to the same, but desire to make such changes as may come within the scope of the novelty involved.

Having thus described my invention, what I claim as new and desire to secure by Letters Patent, is:—

1. A discharge spout for a vehicle consisting of a laterally - deflected body having matched ends, a neck on which either end of said body may be removably mounted by reversal of said body, and means for connecting said neck with the outlet member of said vehicle.

2. An attachment for a discharge spout for a vehicle composed of a laterally-deflected body, a neck on which either end of said body may be removably mounted, and a member extending forwardly from said neck, and adapted to be removably connected with said spout, the upper portion of said member being open.

3. A discharge spout for a vehicle composed of a body, and a neck, with which latter said body is removably connected, said neck having lips adapted to be removably fitted on the outlet member of said vehicle.

4. A discharge spout for a vehicle having an agitating and pushing device thereon, the

same being adapted to enter said spout and engage the contents thereof.

5. A discharge spout for a vehicle having a vane mounted thereon and adapted to enter the body of said spout.

6. A discharge spout, a vane adapted to enter the body thereof, a shaft carrying said vane and mounted on said body, and means for operating said shaft.

10. 7. A discharge spout for a vehicle having

an opening in the wall thereof, a vane adapted to primarily occupy said opening and enter the body of said spout as required, and means for supporting and operating the vane.

JOHN HARBOLSHEIMER.
